Patented May 10, 1927.

1,627,881

UNITED STATES PATENT OFFICE.

ALFRED FELIX SEBASTIEN BELLONE, OF LYON, FRANCE, ASSIGNOR TO SOCIETE CHIMIQUE DES USINES DU RHONE, OF PARIS, FRANCE.

PROCESS FOR THE REDUCTION OF HALOGENATED HYDROCARBONS.

No Drawing. Application filed January 28, 1924, Serial No. 889,169, and in France November 21, 1923.

It has been known for a long time that halogenated hydrocarbons can be reduced into hydrocarbons halogenated to a lesser degree under the action of certain metals. For instance, as early as 1858, Genther (Annalen, Vol. 107, p. 212) has described a process of reduction of carbontetrachloride into chloroform by the use of zinc, and this metal has been used since for the reduction of other halogenated hydrocarbons (see, for instance, the German Patents No. 216,070, of 9th August, 1907, and No. 217,554, of 6th November, 1907). The relatively high cost of zinc, its variable quality, and the difficulty experienced with its recovery, have led to attempts to replace it by iron, but the processes so obtained (see, for instance, the patents taken in U. S. A., No. 753,825, of 9th October, 1902, No. 1,101,025, of 26th July, 1912, and No. 1,311,329, of 8th June, 1914) require the use of iron in the form of a very fine powder, the manufacture of which is itself very costly. Applicant has discovered that the reduction of the halogenated hydrocarbons can be effected in a very simple manner and with quantitative yields, by agitating, at a suitable temperature, the halogenated hydrocarbon to be reduced with ferrous hydroxide in a basic medium. The reaction may be represented diagrammatically by the two following equations, where X represents a halogen atom and R a radical which may be or may not be halogenated:

$$2\text{Fe}(\text{OH})_2 + 2\text{H}_2\text{O} = 2\text{Fe}(\text{OH})_3 + \text{H}_2$$
$$\text{RX} + \text{H}_2 = \text{RH} + \text{HX}$$

These equations correspond to the replacement of an atom of halogen by an atom of hydrogen, but the reaction is equally applicable to the progressive replacement of the halogen atoms contained in a poly-halogenated derivative. For instance, starting from C Cl_4 , one can pass to chloroform or to methylene chloride, and so on, according to the quantity of ferrous hydroxide employed. The quantity of water to use is also, as a minimum, that corresponding to the theoretical needs of the reaction, but it may be much larger, for instance 100 times larger, in order to dissolve certain substances present or for any other purpose, without adversely affecting the reaction. Too great a dilution could, however, in certain cases, entail secondary reactions. The additional quantity of base used must not depart too much from the quantity which must combine with the halogen taken from the halogenated derivative undergoing reduction, if one must not be led to a consumption of ferrous hydroxide greater than that derived from theoretical considerations. Any base may be employed, for instance alkaline or alkaline-earth bases, including magnesia, being guided in the choice by questions of cost. However, weak bases will be advantageously preferred to strong ones, such as soda or potash, when the required product will be sensitive to the action of these strong bases, as is the case, for instance, with chloroform. One can even replace these bases by weak salts of acids, such as carbonates and such like.

It is to be noticed that the reduction is not unfavorably influenced by the presence of any neutral or basic salts such as, for instance, those which contaminate or may contaminate the ferrous hydroxide prepared by the usual known methods. It follows, as a result of evident practical importance, that the ferrous hydroxide may, without inconvenience, be prepared in the midst of the medium itself undergoing reaction, before or during the reaction. It is also not unfavorably influenced by the presence of any liquid, organic or inorganic, neutral or alkaline, chemically inert to ferrous hydroxide, to the halogenated hydrocarbon which is to be reduced, or of the product or products of its reaction, which may be added to the reagents for any particular purpose, for instance for extracting the final product of the reaction or protecting it from the action of the reducing medium as it is generated. The reduction as a rule starts at the ordinary temperature. It is enhanced by good mechanical stirring of the reacting medium. It may be accelerated by heating, through any of the known suitable means, besides the heating arising out of the reaction itself, or on the contrary it may be retarded by cooling.

The reduction may be pushed to its ultimate end or, on the contrary, it may be interrupted before the whole halogenated hydrocarbon to be reduced has undergone the desired transformation. This latter operative method may be thought to be

preferable, for instance, when the product of the reaction is itself liable to be reduced by the ferrous hydroxide.

The product or products of the reaction 5 may be separated from the reacting medium by ordinary distillation or steam distillation, or any other suitable manner.

The apparatus used for the reduction comprises, for instance, a vessel of wood or 10 metal, preferably closed if volatile bodies are either undergoing reaction or produced during the operation. It is provided with an efficient stirrer and, if need be, with any known suitable means of heating or cooling, 15 and with a thermometer and any other means of following the reaction. In the case of the reduction of a volatile body, the apparatus is advantageously provided with a reflux condenser, connected to a distillation 20 column or to any known and suitable condensation device, for instance, if it is desired to separate the products of the reaction by ordinary distillation or by steam distillation.

The ferrous hydroxide necessary to the reduction 25 may be obtained economically, either by electrolysis or by any chemical means, and, as in both cases, its preparation may be carried out simultaneously with the reduction, the process which constitutes the 30 object of the present invention may be worked by either of the four following general types of operating methods:

I. A suitable electrolyte, for instance an aqueous solution of a neutral or basic salt, 35 is placed with the halogenated hydrocarbon to be reduced in an electrolytic apparatus with soluble iron anodes. This electrolytic apparatus may be, for instance, an apparatus of the above type the metallic walls of which 40 will act as cathode, iron anodes passing through the cover (if any).

The current is caused to pass under any desired conditions of voltage and intensity, 45 for instance, the conditions which are known to be most favorable to the generation of ferrous hydroxide.

The reaction begins and proceeds by itself or owing to suitable heating. It is stopped at the desired stage and the product 50 or products of the reaction are separated by any suitable process.

II. The ferrous hydroxide, prepared by any electrolytic method but, except for the presence of the halogenated hydrocarbon to 55 be reduced, kept isolated by any suitable means from the medium in which it has been produced, if desired, or mixed with all or part of this medium, is introduced in a separate reduction apparatus which has been 60 preliminarily filled with the halogenated hydrocarbon to be reduced and a suitable quantity of basic solution.

Generally, the reaction begins by itself; 65 if not, it can be started by suitable heating. The operation is completed as in I.

III. A solution of a ferrous salt is introduced in the reduction apparatus together with the halogenated hydrocarbon to be reduced. The ferrous solution, if desired, may be prepared in the apparatus itself by 70 dissolving iron in an acid. The ferrous hydroxide is precipitated by any known suitable base or basic salt or solution thereof. The operation is completed as in II.

IV. The halogenated hydrocarbon to be 75 reduced, water or any other suitable medium and the necessary quantity of base are introduced in a reaction apparatus, and to the mixture is added the ferrous hydroxide prepared separately by any method, either 80 alone, or in neutral or basic aqueous or other suspension, and, for instance, with the whole or part of the medium within which it has been prepared. The above order, in which the substances are introduced, may be altered 85 or reversed. The operation is completed as in II.

In order to illustrate the present invention, applicant gives below examples of preparation of chloroform by reduction of 90 carbon tetrachloride, according to every one of the above methods.

It will be well understood that these examples do not in the least restrict the invention, and do not preclude in any way any 95 modifications which a man trained in the art could device according to what has been said above.

Example I.—In a tight metallic apparatus, provided with a stirrer and heating coil, 100 and connected to a condenser, are introduced 1,500 c. c. of an electrolyte, such as, for instance, a solution of calcium chloride, the concentration of which is equal to that corresponding to maximum conductivity (that 105 is, about 25%), milk of lime containing 150 grammes of lime, and 500 grammes of carbon tetrachloride.

The apparatus acts as cathode. Iron masses properly insulated from the cover, 110 pass through or are suspended from the latter, and constitute soluble anodes. A sufficient current is caused to pass to obtain the required degree of reduction, for instance, until 90% of the tetrachloride is reduced. 115 The chloroform is then separated by distillation.

Example II.—In an electrolytic apparatus of suitable shape, containing brine (which may advantageously be circulating), a mass 120 of scrap iron, constituting the anode, is acted upon by an electric current (400 ampere hours, for instance). The base formed at the cathode precipitates an equivalent quantity of ferrous hydroxide which can be separated from the bulk of the electrolyte by a suitable means, such as decantation, centrifugation, etc.

This ferrous hydroxide is afterwards 125 transferred to the reduction apparatus, 130

where it is caused to react with 500 grammes of carbon tetrachloride in the presence of 500 grammes of hydrated barium hydroxide, $\text{Ba}(\text{OH})_2 \cdot 8\text{H}_2\text{O}$.

5 *Example III.*—1,800 kilogramme of crystallized ferrous sulphate, 2,000 c. c. of water, 1,750 c. c. of caustic soda of 36° Bé., and 500 grammes of carbon tetrachloride are introduced into an apparatus analogous to the former, but without iron anodes. The mixture is stirred and gradually heated, so as to arrive at the temperature of distillation of chloroform when the reaction is ended.

10 *Example IV.*—400 grammes of iron are caused to be reacted upon by sulphuric acid containing 700 grammes pure acid in a separate apparatus. The ferrous hydroxide, subsequently precipitated by 360 grammes of magnesia, is separated more or less completely from the medium in which it has been generated, and is transferred to a reduction apparatus in order to react with 500 grammes of carbon tetrachloride.

15 What I claim and desire to secure by Letters Patent is:

20 1. The process of reduction of halogenated hydrocarbons and poly-halogenated derivatives of organic compounds consisting in treating said hydrocarbons with ferrous hy-

dioxide in the presence of water and of a substance having a basic reaction, thereby substituting progressively hydrogen for the halogen atoms in said halogenated hydrocarbons and poly-halogenated derivatives.

25 2. The process of reduction of halogenated hydrocarbons and poly-halogenated derivatives of organic compounds according to claim 1, characterized in that the ferrous hydroxide is prepared in the reduction apparatus itself.

30 3. The process of manufacture of chloroform by treating carbon tetrachloride with ferrous hydroxide, in the presence of water and of a substance having a basic reaction.

35 4. The process of manufacture of chloroform by treating carbon tetrachloride with ferrous hydroxide in the presence of water and of lime.

40 5. The process of reduction of halogenated hydrocarbons and polyhalogenated derivatives of organic compounds according to claim 1, characterized in that the ferrous hydroxide is prepared in the reduction liquid itself and this, before the introduction of the halogenated body intended to be reduced.

45 In testimony whereof, I affix my signature.

ALFRED FELIX SEBASTIEN BELLONE.
